PISTON

Harry B. Chaffin, Canton, Ohio

Application July 21, 1936, Serial No. 91,639

3 Claims. (Cl. 309—7)

This invention relates to pistons and, more particularly to those of the type forming the subject-matter of my prior Patent No. 2,012,956, dated September 3, 1935; such pistons including a body portion with laterally-spaced circumferential grooves and a combined bull-and-packing ring composed of lapping arcuate segments jointly providing a plurality of laterally-spaced internal ridges adapted to snugly fit the grooves aforesaid, each said ridge having an inwardly-open groove for reception of appropriate expander means for yieldingly-maintaining the ring segments in fluid-tight contact with a coactive surrounding wall.

15 In practice, pistons of the type referred to have proven generally satisfactory in providing a fluid-tight working-seal with the coactive wall, but it has been discovered that leakage develops between the adjoining end junctures of the combined bull-and-packing ring arcuate segments, and it is the primary aim of this invention to improve such rings so as to positively ensure fluid-tight contact between all of the piston components under all conditions of service.

20 Another object of this invention is to interlock the bull-and-packing ring segments in a manner whereby the normal wear expansion is equally distributed throughout said ring.

25 A further and more specific object is to provide a novel means whereby the arcuate segment circumferential junctures are positively sealed against leakage while being maintained in fluid-tight contact with the surrounding coactive surface.

30 Other and more specific features of the invention residing in advantageous forms and relations of the improved piston structure, hereinafter described, will later on appear and be tersely expressed in the claims at the conclusion of this specification.

In the accompanying drawings:

Fig. I is a face view of a piston in accordance with the present invention, parts being broken out, on planes corresponding with the indicated sections *a—a* and *b—b* in Figs. II and III, to better disclose otherwise hidden features.

Fig. II is a detail cross sectional view on a larger scale, and taken as indicated by the arrows 35 *II—II* in Figs. I and III.

Fig. III is a fragmentary peripheral view, on a larger scale, than Fig. I, showing the outer surface of the piston in linear development.

Fig. IV is a similar view of a slightly modified 40 form of the invention.

Fig. V is a cross sectional view, taken on the plane designated *V—V* in Fig. IV.

Fig. VI is a view corresponding to Figs. III and IV of a further modified form of the invention; and,

Fig. VII is a sectional view on the plane designated by the arrows *VII—VII* in the preceding illustration.

In all of the views, corresponding parts are distinguished by like characters of reference, with 10 added prime exponents to differentiate the modified structures.

Referring more in detail to the drawings, and to Figs. I—III more particularly, the numeral 1 comprehensively designates the piston which has 15 a broad peripheral portion 2 integrally formed with a continuous dished web 3, a central boss 4, and a plurality of laterally-spaced circumferential grooves 5, 5, with an intervening central groove 7. These grooves 5, 5 and 7, are preferably of rectangular-section and of greater depth than width, while it is to be noted the grooves 5, 5 are of corresponding cross-section, whereas the groove 7 is substantially narrower, transversely of the piston 1. The piston 1, may, obviously, be fabricated as a unit, or it may comprise 20 two or more parts appropriately attached together.

The combined bull-and-packing ring, it will be seen, is composed of a series of interchangeable 30 arcuate segments 8, of a width approximating somewhat that of the piston peripheral portion 2, and has internally thereof a pair of laterally-spaced circumferential ridges 9 of a cross-section to snugly fit in the piston grooves 5, 5, hereinbefore referred to. The circumferential ridges 9 are provided with continuous inwardly-open central grooves 10, preferably of a depth greater than their width, and of a cross-section for free 35 reception of suitable split expander-rings 11, having inner flat faces 12 for coaction with the bottoms of the piston grooves 5, 5, and their outer edges 13, preferably of half-round section, for engagement with the similarly rounded bottoms of the ridge grooves 10, although the rings 11 may be of any other desirable cross section or type, without departure from the spirit of the invention, to ensure even engagement throughout the circumferential contacting surfaces of the piston grooves 5, 5, and the expander rings 11, as well 45 as intermediate the latter and the arcuate segments 8. Oil grooves 14 are conveniently provided around the combined bull-and-packing ring.

Referring again to the piston groove 7, it is 50

to be noted that the same is located laterally central with and underneath the position occupied by the inner circumferential junctures 15—Fig. III—of the arcuate segments 8, and said 5 groove is occupied by and substantially filled with a rectangular section outwardly-expanding relatively non-rotative ring 16, which functions to positively maintain a fluid-tight surface contact between its outer periphery 17 and the inner face 10 of said segments, along a circumferential plane spanning the junctures 15 aforesaid.

As wear around the outer peripheral surface 18 of the combined bull-and-packing ring occurs, relative to the contacting surface of a cylinder 15 wall 19, as shown in Fig. II, an outward radial movement of the arcuate segments 8 proportionately takes place; and, in order to distribute the transverse gap 20, thus developed, as well as prevent said gap from growing at one transverse 20 joint between the confronting ends of a pair of segments 8 only, which gap 20 may exceed the length of the circumferential juncture 15 between adjoining segments 8, there is provided an interlocking circumferential juncture 21. As best understood from Fig. III, the interlocking circumferential juncture 21 is preferably constituted by providing each segment 8 with an offset or radial step portion 22, the circumferential faces 23 whereof have a fluid-tight working contact with 30 the confronting faces of the respective segments 8, while the inner transverse faces 24 of the stepped portions 22 are sufficiently separated along radial lines, from one another, to insure between any two adjoining segments a circumferential movement not to exceed a comparatively small percentage of the length of any one segment at their circumferential juncture 15.

In the embodiment of the invention shown by Figs. IV and V, like reference characters are employed with the addition of a prime exponent, in order to avoid unnecessary repetitive description. However, it will be seen the structure involved differs somewhat materially from that shown by Figs. I-III, inclusive, in that the piston 40 peripheral portion 2' is provided with three spaced grooves 5', 5' and 5a (in lieu of the plural grooves 5, 5, before described) and a pair of intervening grooves 1', although any desired odd number of grooves may be utilized according to requirement; while the combined bull-and-packing ring 45 is substantially inset in the piston peripheral portion 2'. In addition, the non-rotatable rings 16' are provided on their inner peripheral surfaces with grooves 25 for reception of round-section split annular expander springs 26, or said 50 rings 16' may be of the snap type or built up with suitable expander means, effective to maintain the rings 16' in firm engagement with the underside of the respective circumferential interlocking junctures 21', afforded by forming the successive arcuate segments 8' with double step portions 22', as will be readily understood, without further explanation herein.

Referring now to Figs. VI and VII, there is

shown a further form of the invention, or a combined bull-and-packing ring differing only from the structure of Figs. I to III, inclusive, in that no outwardly-expanding ring 16 is employed below the circumferential interlocking junctures 21' of the segments 8'. In all other respects this form of the invention conforms with that first described, accordingly like reference characters are employed plus the distinguishing exponent double prime, in order to avoid 10 repetitive explanation.

From the foregoing it will be self evident that an advance in the art has been made by the present invention, or in other words there is provided a combined bull-and-packing ring which 15 can be easily applied, that will function with little perceptible wear, one that can be relied upon to effectively overcome the shortcomings of the patented ring hereinbefore referred to, and which positively ensures a fluid-tight seal 20 during the serviceable life of such packing rings.

Finally, while the invention has been described as preferably adapted to locomotive cylinder pistons, it will be obvious that it is equally applicable to other reciprocating elements, accordingly the right is reserved to not only employ the structure hereinbefore explained in other connections, but to make such minor changes and variations therein as may be found necessary for such other usage, and the scope of the 30 following claims permit.

Having thus described my invention, I claim:

1. In a piston having spaced peripheral grooves, and a combined bull-and-packing ring composed of lapping arcuate segments having internal 35 ridges engageable in said grooves with intervening expander means to uniformly urge the ring outwardly into fluid tight contact with a surrounding wall, step portions on the circumferentially-directed lapping faces of the arcuate 40 segment ends, the inner confronting edges whereof are spaced to define radial gaps, a circumferential groove in the piston peripheral portion below the circumferential juncture of the arcuate segments, and a non-rotative ring fitting in 45 the last mentioned groove spanning the juncture aforesaid and adapted to positively seal said juncture against leakage while maintaining the ring segments in fluid-tight contact with a surrounding coactive wall. 50

2. The combination of claim 1, wherein the piston circumferential groove is of rectangular cross-section, and the non-rotative ring is split and expandingly fits into said groove, for the purpose specified. 55

3. The combination of claim 1 wherein the piston periphery has plural grooves with intervening non-wearing material ring receiving grooves, the combined bull-and-packing ring segments have complementary ridges engageable in the plural grooves, and the non-rotative rings have inwardly open grooves for reception of suitable expander elements, for the purpose specified. 60

HARRY B. CHAFFIN.
